DESIGN FOR A TEXTILE FABRIC

Leo Schwartzberg, New York, N. Y.

Application November 12, 1940, Serial No. 96,596

Term of patent 3½ years

To all whom it may concern:

Be it known that I, Leo Schwartzberg, a citizen of the United States and a resident of the city of New York, in the county of New York and State of New York, have invented a new, original, and ornamental Design for a Textile Fabric, of which the following is a specification, reference being had to the accompanying drawing, forming a part thereof.

The figure is a plan view of a piece of the fabric showing my new design, the unit of which is indicated by dot-and-dash lines.

I claim:

The ornamental design for a textile fabric, substantially as shown.

LEO SCHWARTZBERG.
